McElveen & Allen

UNITED STATES PATENT OFFICE.

EDWARD WILBUR HILL, OF CHICAGO, ILLINOIS.

HEET-EDGE PROTECTOR.

1,250,174.

Specification of Letters Patent. Patented Dec. 18, 1917.

Application filed November 14, 1916. Serial No. 131,243.

To all whom it may concern:

Be it known that I, EDWARD W. HILL, a citizen of the United States of America, residing at Chicago, Illinois, have invented a new and useful Sheet-Edge Protector, of which the following is a specification.

My present invention has for its objects to protect the perforated edge portions of the leaves used in loose leaf books and particularly to prevent the tearing of such edge portions when inserting the leaves in typewriter and such other machines.

In the accomplishment of the foregoing I provide a suitable backing sheet for the leaf to be protected and a guard strip flexibly connected with the backing sheet and disposed so as to overlie and protect the perforated edge portion of the leaf.

Another feature is the provision of means for gaging the leaf as it is inserted in the protector.

Other features of the invention will appear as the specification proceeds, attention being directed to the accompanying drawing forming a part hereof and wherein I have illustrated the invention embodied in a practical commercial form.

In said drawing:

Figure 1, is a fragmentary perspective view showing the invention as in use for protecting a loose ledger sheet inserted in a typewriter machine.

Fig. 2, is a plan view of the protector showing the guard strip folded over into protective position on the leaf, in dotted lines.

Fig. 3, is a broken enlarged sectional view of the protector as in use, taken substantially on the plane of the line 3—3 of Fig. 2.

In the illustration I have shown a loose ledger leaf 5 of typical construction having "split openings" 6 in the vertical side margin thereof to fit the binding posts of an ordinary binder.

Great difficulty has heretofore been experienced in handling these leaves in typewriter machines for the reason that the tongues provided by the split openings in the edge of the sheet naturally catch on the paper guides, scale, line gages and other elements of the typewriter causing tearing of the marginal portion of the leaves and thereby ruining the leaves for binding purposes.

To overcome this I have provided the protector here disclosed, comprising a backing sheet 7 on which the leaf is superposed and

having a guard strip 8 flexibly attached thereto and arranged to overlie the vertical side edge of the leaf in which the binding perforations are located. This guard strip 60 may conveniently be formed as an integral portion of the backing sheet, it being herein shown flexibly hinged to the edge portion of the backing sheet along the line 9 and detached from the sheet for the balance of its 65 length as indicated at 10.

In use the leaf is placed on the backing sheet with its perforated edge overlying the edge portion of the backing sheet and the guard strip is folded over so as to cover the 70 perforated edge portion of the sheet, substantially as indicated in Fig. 2. The guard strip protects the split edge of the leaf and causes it to feed smoothly through the machine.

The guard strip being free for a greater portion of its length adjusts itself automatically in going through the machine and prevents any creasing or folding of either the backing sheet or the edge of the leaf.

The backing sheet is, for the purposes of protection and for convenience in handling, made substantially the same size as the leaf to be protected.

For the purpose of quickly gaging the leaf 85 in the protector and temporarily holding the parts together there may be provided a gaging device such as that indicated and consisting of a tongue 11 cut from the edge portion of the backing sheet as by means of 90 an arcuate cut 12 and arranged to receive beneath it the side edge of the leaf as the leaf is applied to the backing sheet.

This construction provides a means for quickly and automatically side registering 95 the leaf within the protector and does not interfere with jogging the two papers as is usually done to bring the front edges into register.

The device, it will be seen, is simple, inexpensive and serves to efficiently protect the heretofore troublesome and unprotected perforated edges of ledger leaves.

What I claim is:

1. A protector for leaves having split openings along one edge thereof, comprising a backing sheet to be disposed at the back of the leaf, having a guard strip hinged along a portion of one edge thereof and disconnected from the balance of said edge to thereby provide a flap which can be folded 100 over the perforated edge of the leaf.

2. A protector for leaves having split openings in the edges thereof comprising a backing sheet having a stop located inward from one edge thereof to form a side gage
5 for the perforated edge of a leaf, and a flap disposed parallel to said edge of the backing sheet arranged to overlie the stop aforesaid and the split edge of the leaf registered against said stop, said flap being hinged along said edge for a portion of its length 10 and being disconnected from said edge for the balance of its length.

EDWARD WILBUR HILL.
